US0D1099536S

(12) **United States Design Patent** (10) **Patent No.:** **US D1,099,536 S**
(45) **Date of Patent:** **** Oct. 28, 2025**

(54) **PURSE**

(71) Applicant: **CORE M MIESZCZAK SPÓŁKA KOMANDYTOWO-AKCYJNA, Wrocław (PL)**

(72) Inventor: **Piotr Siegieńczuk, Wrocław (PL)**

(73) Assignee: **CORE M MIESZCZAK SPÓŁKA KOMANDYTOWO-AKCYJNA, Radomska (PL)**

(**) Term: **15 Years**

(21) Appl. No.: **29/968,569**

(22) Filed: **Oct. 17, 2024**

Related U.S. Application Data

(62) Division of application No. 35/519,061, filed on Jul. 25, 2023 (U.S. filing date under 35 U.S.C. 384), and having an international filing date of Jul. 25, 2023, now abandoned.

(51) **LOC (15) Cl.** **03-01**

(52) **U.S. Cl.**

USPC **D3/230**
